United States Patent Office

Des. 207,678
Patented May 16, 1967

207,678

JUG

James E. Cunningham, Islington, Ontario, Canada, assignor to Witco Chemical Company, Inc., New York, N.Y., a corporation of Delaware

Filed Sept. 10, 1965, Ser. No. 86,929

Term of patent 14 years

(Cl. D58—5)

FIG. 1 is a side view in elevation of a jug, showing my new design;

FIG. 2 is an end view in elevation thereof as viewed from the right of FIG. 1;

FIG. 3 is an end view in elevation thereof as viewed from the left of FIG. 1; and

FIG. 4 is a top plan view thereof.

I claim:

The ornamental design for a jug, substantially as shown.
